ALBERT C. MENGES, OF GRAND RAPIDS, MICHIGAN, ASSIGNOR TO
WILLIAM HARRISON, OF GRAND RAPIDS, MICHIGAN.

IGNITER.

No. 836,521.

Specification of Letters Patent.

Patented Nov. 20, 1906.

Application filed January 9, 1906. Serial No. 295,274.

To all whom it may concern:

Be it known that I, ALBERT C. MENGES, a citizen of the United States, residing at Grand Rapids, in the county of Kent and State of Michigan, have invented new and useful Improvements in Igniters, of which the following is a specification.

This invention relates to new and useful improvements in igniters for explosive-engines. Its object is to provide an efficient and simple igniter and maintain it in operative condition.

It is well known that in the use of igniters which have a bar extending through the cylinder-head into the interior of the cylinder and surrounded, as such bar must be, by insulating material there is a tendency for the materials found in the interior of the cylinder, and especially for carbon, the result of the combustion there taking place, to collect upon this insulating material and make a deposit thereon and in connection therewith, which will establish a circuit between the igniter-bar and other adjacent parts of the mechanism; so as to prevent the formation of the desired spark at the proper place, and to avoid this difficulty is the more special object of my invention. This object I accomplish by the mechanism shown in the accompanying drawings, in which—

Figure 1 is a vertical cross-section of my device ready for insertion into the cylinder-head, the cross-section being taken on line *x x* of Fig. 2. Fig. 2 is a side plan of the same parts, a portion being broken away to show interior parts.

5 is the igniter-bar, made of any suitable material and extends from the outside of the cylinder-head through into the interior. It is preferably threaded upon both ends, as shown.

6 is a binding-nut adapted to clamp down the circuit-wire, the upper end of the bar 5 thereof serving as a binding-post.

45 1 is an insulating-sleeve, made from porcelain or other suitable material, wholly surrounding the igniter-bar. At its upper end it is provided with a cap 7, making engagement with the screw-thread of the igniter-bar and holding the sleeve from movement in that direction. At its lower end it is provided with a suitable depression to receive the threaded nut 8, which is screwed up against the resulting shoulders and holds the sleeve

from movement in that direction. 2 is a 55 metal sleeve surrounding this insulating-sleeve, having the outward projection shown and having the external screw-thread 11 and having at the lower end the bead 14.

3 is a lock-nut, and 4 represents an external thread on a portion of the sleeve 2 and an internal thread on the lock-nut 3. This sleeve 2 and this nut 3 are provided with or constitute shoulders which engage with corresponding shoulders on the insulating-sleeve 65 1, and thereby hold it from motion in either direction with reference to the parts external to it.

10 is a washer or disk, closing the lower end of sleeve 2, held in position by the beading 14 70 and having the central opening shown in Fig. 1.

9 is a loose sleeve or ferrule surrounding the lower part of the insulating-sleeve 1. It is prevented from moving upward very far 75 by the shoulder shown on sleeve 1, and it is prevented from falling down out of position by the washer 10. It is not connected either with the insulating-sleeve within it or with the metal sleeve outside of it, but is free to 80 vibrate and shake and rap against the adjacent parts.

13 13 are notches or open spaces in the lower part of the sleeve to permit the gas more freely to enter within the same, and 85 12 12 are notches or corrugations upon the upper edge of the sleeve, whereby it may more efficiently scrape the insulating-surface of the sleeve 1.

15 15 represents notches or openings in the 90 lower edge of sleeve 2 to permit the gas more freely to enter the interior of the sleeve.

It is evident that the various parts of my device can be assembled without difficulty into the form shown in Fig. 1, making the 95 device complete. It is then screwed down into the ordinary screw-threaded opening in the cylinder-head, the thread 11 engaging with the internal thread upon the opening in the cylinder-head, and it is screwed down 100 tightly until the projecting portion of sleeve 2 engages with the external face of the cylinder-head. Then when the electric current is passed through the igniter-bar a jump-spark will be formed between the lower end of the 105 igniter-bar and the nearest portion of the washer 10, and this spark being properly timed with reference to the presence of ex-

losive gas in the cylinder an explosion will follow. Evidently this explosive gas, being under considerable pressure, will fill all the open spaces within the sleeve 2 and inside the cylinder, and the explosion will cause a great shock and vibration at this point. Thereby the loose sleeve 9 will be jarred and shaken against and upon the parts adjacent to it on both sides and above and below, and it will scrape or knock or jar loose the carbon and other deposits that otherwise would form. There will be a repetition of this jarring and shaking and knocking at every explosion; and it will be found impossible for any considerable deposit to form or for any short circuit to result.

Having thus described my invention, what I claim to have invented, and desire to secure by Letters Patent, is—

An igniter for explosive-engines, comprising an igniter-bar, an insulating-sleeve, a jarring member, and means for loosely retaining the jarring member in continual proximity to the adjacent parts. 20

In testimony whereof I have hereunto set 25 my hand in presence of two subscribing witnesses.

ALBERT C. MENGES.
